US00D966216S

(12) **United States Design Patent** (10) **Patent No.:** **US D966,216 S**
(45) **Date of Patent:** **** Oct. 11, 2022**

(54) **TELEVISION RECEIVER**

(71) Applicant: **LG ELECTRONICS INC.**, Seoul (KR)

(72) Inventors: **Nari Lee**, Seoul (KR); **Wosuk Park**, Seoul (KR); **Sangik Lee**, Seoul (KR)

(73) Assignee: **LG ELECTRONICS INC.**, Seoul (KR)

(**) Term: **15 Years**

(21) Appl. No.: **35/512,552**

(22) Filed: **Mar. 16, 2021**

(80) **Hague Agreement Data**

Int. Filing Date: **Mar. 16, 2021**

Int. Reg. No.: **DM/213442**

Int. Reg. Date: **Mar. 16, 2021**

Int. Reg. Pub. Date: **Sep. 17, 2021**

(30) **Foreign Application Priority Data**

Sep. 23, 2020 (KR) 30-2020-0045981

(51) **LOC (13) Cl.** **14-03**

(52) **U.S. Cl.**

USPC **D14/126; D14/452**

(57) **CLAIM**

The ornamental design for a television receiver, as shown and described.

DESCRIPTION

1. Television receiver

1.1 : Front Perspective view shown in the first position

1.2 : Rear Perspective view shown in the first position

1.3 : Front view shown in the first position

1.4 : Rear view shown in the first position

1.5 : Left view shown in the first position

1.6 : Right view shown in the first position

1.7 : Top view shown in the first position

1.8 : Bottom view shown in the first position

1.9 : Front perspective view shown in the second position

1.10 : Rear perspective view shown in the second position

1.11 : Front view shown in the second position

1.12 : Rear view shown in the second position

1.13 : Left view shown in the second position

1.14 : Right view shown in the second position

1.15 : Top view shown in the second position

1.16 : Bottom view shown in the second position

1.17 : Front view shown with a rotating display panel

1.18 : Front perspective view shown in the third position

1.19 : Rear perspective view shown in the third position

1.20 : Front view shown in the third position

1.21 : Rear view shown in the third position

1.22 : Left view shown in the third position

1.23 : Right view shown in the third position

1.24 : Top view shown in the third position

1.25 : Bottom view shown in the third position

1.26 : Top view shown with a rotating display panel

(Continued)

1.27 : Rear perspective view shown in the fourth position
 1.28 : Second rear perspective view shown in the fourth position
 1.29 : Right view shown in the fourth position
 1.30 : Left view shown in the fourth position
 1.31 : Front view shown in the fourth position
 1.32 : Rear view shown in the fourth position
 1.33 : Top view shown in the fourth position
 1.34 : Bottom view shown in the fourth position
 1.35 : Right view shown with a lifted display
 1.36 : Rear perspective view shown in the fifth position
 1.37 : Second rear perspective view shown in the fifth position
 1.38 : Right view shown in the fifth position
 1.39 : Left view shown in the fifth position
 1.40 : Front view shown in the fifth position
 1.41 : Rear view shown in the fifth position
 1.42 : Top view shown in the fifth position
 1.43 : Bottom view shown in the fifth position
 The subject design features a dual hinge between the display panel and the stand that allows the display panel and the stand to move up and down, rotate and lift; the broken lines indicate portions of the article that form no part of the claimed design; reproduction 1.1 to 1.8 show the television in the first position; reproduction 1.9 to 1.16 show the television in the second position; reproduction 1.18 to 1.25 show the television in the third position; reproduction 1.27 to 1.34 show the television in the fourth position; reproduction 1.36 to 1.43 show the television in the fifth position; reproduction 1.17 is a reference view showing the status of rotating display panel; reproduction 1.26 is a reference view showing the status of rotating display panel; reproduction 1.35 is a reference view showing the status of lifting display panel.
